PENCIL SHARPENER

Philip Fletcher, Chambersburg, Pa.

Application April 9, 1942, Serial No. 438,333

3 Claims. (Cl. 120—93)

This invention relates to a pencil sharpener.

It is primarily aimed to provide such an article which will constitute an attachment for the ordinary lead or other writing pencil, to be carried removably on the latter, and capable of mounting and being closed by the eraser of the pencil.

It is particularly aimed to provide a structure which may be made tubular and relatively short, with a diagonal blade therein fastened at opposite ends and generally reinforcing the structure. To render it more practical, an attaching clip whereby the article may be secured to a coat pocket or the like has been employed.

In addition, it is aimed to provide a novel structure which may have a window for viewing the interior thereof and which may be made in separable sections.

The more specific objects and advantages will become apparent from a consideration of the description following taken in connection with accompanying drawings illustrating an operative embodiment.

In said drawing:

Figure 1 is a view in elevation showing my improvements, preferably with a point protector shown in sections and with a cap also shown in sections;

Figure 2 is an enlarged view primarily in section taken on the plane of line 2—2 of Figure 1; and

Figure 3 is an enlarged section taken on the plane of line 3—3 of Figure 2.

Referring specifically to the drawing wherein like reference characters designate like or similar parts, my improvements consist of a tube 10 of any suitable size and material, in the lower end of which a socket member 11 is screw threaded or otherwise detachably connected at 12. The tube 10 is preferably of somewhat thicker material than the section 11. The latter section preferably has a partition wall at 13. Section 11 is open at the bottom in order to provide a socket 14 for detachable frictional engagement with the upper end of an ordinary lead or other pencil 15.

A sharpening blade is shown at 16 disposed with a cutting edge at 17. This blade is disposed approximately diametrically of the tube 10 and also diagonally with respect to the vertical or the longitudinal axis of tube 10 as best shown in Figure 2, the opposite ends of such blade being fastened as shown by welding or in any suitable manner, in the wall of tube 10. As a result, the tube is greatly strengthened by the blade so as especially to enable the attachment of a clip 18 to the tube and manipulation of the tube in attaching the clip 18 to and from a pocket of a coat or the like.

The angular disposition and end fastening of the blade also greatly strengthen the tube for its

function as a pencil sharpener. Pencil 15 may be readily detached and its lower end inserted into the upper end of tube 10 and the same turned relatively so that the blade 16 will function as 5 a pencil sharpener.

The upper open end of the tube 10 is adapted to be closed by a pencil eraser 19 of conventional structure, usually rubber, with an abrasive dispersed therethrough. In addition, a cap 20 may be employed, if desired, the same detachably engaging screw threads 21 on the upper end of the tube 10.

As an accessory, I may provide a point protector 22 which is slidably engageable and disengageable with the pencil as shown in Figure 1, the same being of any suitable material and adapted to remain in place by reason of a friction fit.

Tube 10 may have a window opening 23 therein 20 adjacent its base so that one may view the progress of a pencil sharpening operation and the accumulation of shavings therein, to best judge when to empty the same by detaching the tube 10 at 12 from the holder 11. This opening 23 25 may be covered by a case of Cellophane or any other desired transparent or translucent material 24.

Various changes may be resorted to provided 30 they fall within the spirit and scope of the invention as hereinafter defined by the appended claims.

I claim as my invention:

1. A pencil sharpener attachment of the class described comprising a tube, a blade disposed 35 generally diagonally and diametrically within the tube and fastened at opposite ends to the latter, said blade at its intermediate portion being narrow and free from the wall of the tube to provide much room on all sides of the blade, and 40 means to fasten the tube to a pencil.

2. A pencil sharpener attachment of the class described comprising a tube, a blade disposed generally diagonally and diametrically within the tube and fastened at opposite ends to the latter 45 and adjacent opposite ends of the latter, said blade at its intermediate portion being narrow and free from the wall of the tube to provide much room on all sides of the blade, and means to fasten the tube to a pencil, comprising an attaching section, and means separably connecting the tube and attaching section.

3. A pencil sharpener of the class described 55 comprising a tube, a blade disposed generally diagonally and diametrically within the tube and fastened at opposite ends to the latter, said blade at its intermediate portion being narrow and free from the wall of the tube to provide much room on all sides of the blade.
